[57] **CLAIM**

The ornamental design for a combined tube and cap, as
shown and described.

DESCRIPTION

FIG. 1 is a front elevational view of a combined tube
and cap showing my new design;

FIG. 2 is a top, front and side perspective view thereof;
FIG. 3 is a top plan view thereof;

FIG. 4 is a bottom plan view thereof; and,

FIG. 5 is a side elevational view thereof, the undis-
closed opposite side being a mirror image.

The characteristic feature of the design resides in the
unique dispensing opening having a mushroom shape.

FIG. 1

FIG. 2

FIG. 5

FIG. 3

FIG. 4
